(57) **CLAIM**

The ornamental design for a slatted rail equipment mount, as shown and described.

DESCRIPTION

FIG. 1 is a top perspective view of a slatted rail equipment mount;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken line showing of a long, horizontal rectangle in FIGS. 1 and 2 depict portions of the slatted rail equipment mount. The remaining broken lines illustrate an environment of use. The broken lines form no part of the claimed design.
